(57) **CLAIM**

What is claimed is the ornamental design for an LED lanyard, as shown and described.

DESCRIPTION

FIG. 1 is a perspective view of an LED lanyard, showing the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in FIG. 3 depict environmental matter and form no part of the claimed design.

The lanyard portion of the design is shown broken away along its length to indicate a non-specified length.

1 Claim, 3 Drawing Sheets
